UNITED STATES PATENT OFFICE.

JAMES DUVALL, OF CAMAS, WASHINGTON.

PNEUMATIC PRESS-FEEDING MEANS.

1,076,491.

Specification of Letters Patent. Patented Oct. 21, 1913.

Application filed March 7, 1912. Serial No. 682,302.

To all whom it may concern:

Be it known that I, JAMES DUVALL, a citizen of the United States, and resident of Camas, county of Clarke, State of Washington, have invented a new and useful Improvement in Pneumatic Press-Feeding Means, of which the following is a specification.

My invention relates to automatic printing presses, especially those used for printing paper bags, provided with a pneumatic compression cylinder and automatic intermittent feeding mechanism, whereby the outermost sheet of a stack of material is periodically moved toward the printing mechanism.

The object of my invention is the providing of more efficient automatic means for carrying the outermost of the material stacked on the feeding apron to the compression cylinder, also properly, relatively timing the coöperating mechanism.

In illustrating my invention I have shown a common type of printing mechanism used for printing paper bags, comprising a type cylinder and a pneumatic compression cylinder in which a partial vacuum is caused by convenient suction means.

The specific beneficial results obtained by me, the details of the devices used by me for this purpose, and the mode of operation, will be hereinafter fully described.

In the accompanying drawings: Figure 1 is a side elevation of a bag printing press of the type referred to embodying my invention; this view also shows the valve controlling the connection between the compression cylinder and the suction element (the latter not being shown) also the automatic means actuating said valve; Fig. 2 is an end elevation of said press looking in the direction pointed by the arrow in Fig. 1, the endless feeding apron being shown in section and the cut-off valve controlling the connection between said compression cylinder and the suction element being omitted; Fig. 3 shows a larger-scale view of the compression cylinder looking in the direction pointed by the arrow in Fig. 1, illustrating the provision of auxiliary means, viz. nippers, for holding the material to be printed on the compression cylinder; the upper half of this figure is drawn in section so as to show the arrangement of the parts, the bearings for the compression cylinder, and the connection between the latter and the suction element;

Fig. 4 is a section on the line 4—4 of Fig. 3, looking in the direction pointed by the arrow; Fig. 5 is a perspective detail illustrating the construction and operation of the valve controlling the connection between the compression cylinder and the suction element; Fig. 6 is a diagrammatic view illustrating the action of and the means for actuating said valve, also the relative movement of a hollow hinged pendent suction arm provided for carrying the outermost of the sheet of stacked material to the compression cylinder; Fig. 7 is a diagrammatic perspective detail of said hollow arm and its operative connections; Figs. 8 and 9 are perspective details of a pawl and ratchet element and connections for intermittently operating the feeding apron; Figs. 10 to 12, inclusive, illustrate the action of said auxiliary nippers shown in Figs. 4 and 6, namely: Fig. 10 is a diagrammatic view illustrating in broken lines the operation of the cam-like means for locking against rotation the shaft supporting the auxiliary nippers, and showing in full lines the adjustable plate carrying the cam pins with which said cams are brought into contact at proper intervals for throwing said auxiliary nippers into and out of their active position; Fig. 11 is a diagrammatic side elevation, on a larger scale, of said cam mechanism; Fig. 12 is a diagrammatic elevation of said cam mechanism; Fig. 13 is a fragmental section illustrating the construction of the spring-controlled stud pin for locking the cam in place after having been thrown into one position until forcibly thrown into another position by coming in contact with said cam pins provided on the plate shown in Fig. 10; Fig. 14 is a diagrammatic view illustrating a modification, as follows: here the relative positions of the compression cylinder and the type cylinder have been changed, and the hollow pendent arm provided for carrying the outermost sheet of stacked material to the compression cylinder is rigidly instead of hingedly supported; Fig. 15 diagrammatically illustrates another modification, here the compression cylinder and type cylinder are mounted in a common plane, and the material is arranged in a vertical stack, and the devices are correspondingly arranged so as to pick off the uppermost of such stack and pull it toward the compression cylinder; and Fig. 16 is a diagrammatic illustration of a further modi-

ification in the arrangement of the coöperating parts of my invention, in this, the material to be printed is moved intermittently along a horizontal plane, the individual sheets being set on an end on a horizontally extending feeding apron, and the devices are arranged to operate without the aid of a hollow suction arm for carrying the outermost sheet to the compression cylinder.

10 The bag printing press shown is of the usual type, and has combined with it a suction compression cylinder *a*, arranged relatively to the type cylinder *b*, provided with a plurality of suction orifices *j*. The details not entering into the novelty of my invention are not illustrated.

15 The bags to be printed are stacked on a horizontally arranged endless apron *d*, which feeds the material toward an oscillating hollow suction arm movably, (*e*, as shown in Figs. 1 and 6) or rigidly, (*e'*, as shown in Fig. 14) connected to the exhaust pipe *g*, which is connected to suitable vacuum causing means not shown. If the suction arm be movable, as shown at *e* in Figs. 1, 2 and 6, such arm is suspended by a hinge joint, *f*, to the exhaust pipe *g*, and is oscillated by a rod *h*, actuated by a crank pin *i*, mounted on the axle end, *l*, of the compression cylinder *a*, the devices operating as diagrammatically illustrated in Fig. 7.

20 The endless apron *d* is supported by rollers as *r* (supports for one end only being shown) journaled in posts *s'* mounted on the frame *s*. The apron *d* is moved forward by the rotation of the roller *r*, which is accomplished by a pawl as *u* and ratchet wheel *t*, the latter being mounted on the axle end *r'* of the roller *r*. As shown in Fig. 8, the 25 pawl *u* consists of a plurality of members of graded sizes, as 14, 15, 16 and 17, pivoted on the upper end of the rod *v*, the lower end of which is pivoted on a crank pin, *x*, adjustably supported in a slotted plate *y*, affixed on the end of type-cylinder axle *b'*. See Figs. 2 and 9. The upper end of the 30 rod *v* at the pivotal point of said pawl members is connected by links *w* with said axle end *r'*, as shown in Figs. 1, 8 and 16. The upper end of the rod *v* is reciprocated by the movement of the crank pin *x*, as apparent. Thus the forward motion of the ratchet wheel *t*, and therewith the apron *d*, may be adjusted relatively to the thickness 35 of the bag, for by the adjustment of the crank pin *x* relatively to the center of the axis *b'* the degree of forward movement of the ratchet wheel *t* may be made any multiple of the pitch of its teeth. For example, when four pawl members are used, as shown in Fig. 8, and the bags to be printed are very thin, the crank pin *x* will be so adjusted that each pawl member will act in turn to rotate the ratchet wheel *t* 40 one-fourth of its pitch.

The bags are held in alinement on the apron *d* by means of the adjustable side rails mounted on the frame *s* by some suitable support, as shown at *s'* in Fig. 1. When an oscillating suction arm, as *e*, is included 70 in the construction of my device, the outermost bag of the stack, *c*, is seized by such arm when the latter is positioned as illustrated in dotted lines in Figs. 1 and 6; and the return of such suction arm to its position in full lines in the same figures, brings the lower edge of such outermost bag opposite the suction holes *j* of the compression cylinder *a*; the operation of the devices being timed accordingly. A suction is caused 75 through the compression cylinder, *a*, by any convenient means, and such suction holds the bag in place on the compression cylinder during the interval of the printing operation.

80 The sleeves 2 and 9 provide a connecting passageway between the cylinder, *a*, and the exhaust pipe 10, through the medium of the valve-seat 3. See Fig. 3. The pipe 10 is connected with the suction means.

85 The suction through the compression cylinder *a* is controlled by means of a cut-off valve *p*, provided with a finger *p'* and actuated by a cam segment *q*, rigidly attached to a gear 7, which is mounted on one axle-end of the compression cylinder *a*. The valve *p* is normally held in its closed position by a coil-spring 6, shown in Figs. 1 and 5, and once during each revolution of the compression cylinder, *a*, the finger *p'* of the 90 valve *p* comes into contact with the cam segment *q*, thus opening the valve and so holding it as long as said contact continues; and after the cam has passed from the finger *p'* of the valve the spring 6 acts to instantly 95 close the valve again. Nippers *k* are also provided in a box-like cavity in the compression cylinder, *a*, as shown in Figs. 4 and 6, and operated by a cam element *m*, arranged as diagrammatically shown in Figs. 100 10, 11 and 12. The cam element, *m*, is actuated by pins *n* set at predetermined positions in an adjustable plate *o*, hung on one axle-end of the compression cylinder *a*, substantially as shown in Figs. 3, 10 and 11. 105 The cam element, *m*, is automatically locked against movement at certain intervals by a lock-pin 8, constructed and arranged as illustrated in Figs. 11 and 13, these devices operating substantially as used at present 110 in other press mechanisms.

115 Instead of using an oscillating suction arm one may be used arranged in fixed position, as shown at *e'* in Fig. 14. In such case the feeding apron *d* must operate closer to the compression cylinder, and the mouth of the suction arm must be located close to the feeding apron *d*. The relative positions of the cylinders, *a*, *b*, may be varied, as 120 illustrated in Fig. 15. When a suction arm 125 130

is not to be used a plate 11 must be provided, as shown in Fig. 16. This plate is supported by a bracket 19 on the frame *s*, and holds the outermost bag in such position that the 5 suction through the holes of the compression cylinder will pull it into contact with the latter.

In order to conveniently arrange the device so as to cause the feeding apron to feed 10 the bags as close to the compression cylinder as possible, longitudinally arranged strips 12 are provided, supported on the frame *s* by brackets 18, over the apron *d*, as shown in Fig. 16. These strips are spaced 15 apart, and on the feeding apron are mounted transverse cleats, or other protruding surface, (not shown) for engaging with the bottom ends of the bags, between the strips 12, in so doing moving the bags forward. 20 The details of construction entering into the last described device will suggest themselves to any practical mechanic by having reference to Fig. 16, and hence a further description thereof is unnecessary.

25 The arrangement of the devices as shown in Fig. 15 is apparent from the brief description of, and the inspection of, such figure; the parts corresponding with those specifically described bearing like reference 30 characters. The shield 20 prevents the suction through the orifices of the compression cylinder from acting on the material *c* until the suction orifices have arrived at the point 21. Otherwise the top bag might be 35 moved out of proper place before it is picked up.

40 The means providing a partial vacuum in the compression cylinder, *a*, and in the suction arms, *e* or *e'*, must be adapted to cause the suction to be greater in said cylinder than said arm, so that the former will pull the bag or sheet of material from the latter.

I claim:

45 1. The combination with a press comprising a vacuum compression cylinder and traveling means for carrying stacked material toward said cylinder, the delivery end of said carrying means being spaced from said cylinder, of feeding means comprising 50 a suction element located above the space between said cylinder and said carrying means, a rockable pendent mouth-end suspended from such suction element between said cylinder and said carrying means, and means for moving said rockable mouth-end to and fro between the carrying means and said cylinder, said moving means timed with the action of the latter.

60 2. The combination with a press comprising a vacuum compression cylinder and traveling means for carrying stacked material toward said cylinder, the delivery end of said carrying means being spaced from said cylinder, of feeding means comprising 65 a suction element located above the

space between said cylinder and said carrying means, a rockable pendent mouth-end suspended from such suction element between said cylinder and said carrying means, said mouth-end formed with a bevel 70 face turned toward the delivery end of said carrying means, and means for moving said rockable mouth-end to and fro between the carrying means and said cylinder, said moving means timed with the action of the 75 latter.

3. In a press comprising a type-cylinder and a compression-cylinder, an endless apron for feeding the material to the latter, said apron supported at its ends by 80 rotatable rollers, means for driving said apron consisting of a ratchet-wheel mounted on the axis of one roller; a crank pin on one end of the type-cylinder, a rod pivoted at its lower end on said crank-pin; a pawl pivoted on the upper end of said rod, said pawl consisting of a plurality of graded members resting on said ratchet wheel; and means pivotally supporting the upper end of said rod and therewith the pawl members 90 in operative relation to the ratchet wheel.

4. In a press comprising a type-cylinder and a compression-cylinder, an endless apron for feeding the material to the latter, said apron supported at its ends by 95 rotatable rollers, means for driving said apron consisting of a ratchet-wheel mounted on the axis of one roller; an adjustable crank pin on one end of the type-cylinder, a rod pivoted at its lower end on said crank-pin; 100 a pawl pivoted on the upper end of said rod, said pawl consisting of a plurality of graded members resting on said ratchet wheel; and means pivotally supporting the upper end of said rod and therewith the 105 pawl members in operative relation to the ratchet wheel.

5. In press feeding means of the character described, a rotating hollow compression cylinder provided with circumferential suction aperture or apertures, also provided with an exhaust orifice, and means for connecting the latter with a suction element; a spring actuated gate controlling said exhaust orifice, said gate formed with a projecting finger, and a cam affixed to the compression cylinder, adapted to engage with the finger of said gate and open the latter during each revolution of the compression cylinder.

6. In press feeding means of the character described, a rotating hollow compression cylinder provided with circumferential suction aperture or apertures, also provided with an axial exhaust orifice and 125 means for connecting the latter with a suction element; a spring actuated gate controlling said axial exhaust orifice; and said gate formed with a projecting finger, a cam affixed to the compression cylinder, adapted 130

to engage with the finger of said gate and open the latter during each revolution of the compression cylinder.

7. In press feeding means of the character described, in combination with means providing an intermittent feed of stacked material, a rotating hollow compression cylinder provided with circumferential suction aperture or apertures, also provided with 10 an axial exhaust orifice and means for connecting the latter with a suction element; a spring actuated gate controlling said axial exhaust orifice; said gate formed with a projecting finger, a cam affixed to the compression cylinder, adapted to engage with 15

the finger of said gate and open the latter during each revolution of the compression cylinder; a hinged hollow arm adapted to be connected to said suction element, said arm movable between the material stacked 20 on said intermittent feeding mechanism and said compression cylinder and operating to carry the outermost sheet of the stack to the latter; and means operating said hollow arm in synchronism with the printing 25 operation.
